[57] **CLAIM**

The ornamental design for the portable data terminal, as shown and described.

DESCRIPTION

FIG. 1 is an isometric view of the portable data terminal of our new design, showing the front, and right side with the handle rotated to a first support position and with the front panel closed;

FIG. 2 is an isometric view thereof showing the rear, bottom, and left side, the handle and front panel in the position shown in FIG. 1;

FIG. 3 is an isometric view similar to FIG. 1, but showing the front panel open;

FIG. 4 is an isometric view of the terminal being in a vertical position with the front panel closed and the handle rotated to a carry position;

FIG. 5 is an isometric view of the terminal on a reduced scale, the terminal being in a vertical position with the front panel open and the handle rotated to a second support position.

The keyboard is shown in broken lines on the inside surface of the front panel for illustrative purposes only.
